UNITED STATES PATENT OFFICE.

WILFRID LAWSON ROBERTSHAW, OF LAWRENCE, MASSACHUSETTS.

DESIGN FOR A DEVICE FOR TAMPING TOBACCO IN PIPE-BOWLS.

43,450.

Specification for Design.

Patented Jan. 14, 1913.

Application filed August 28, 1912. Serial No. 717,614. Term of patent 7 years.

To all whom it may concern:

Be it known that I, WILFRID L. ROBERTSHAW, a citizen of the United States, residing at Lawrence, in the county of Essex and State of Massachusetts, have invented a new, original, and ornamental Design for a Device for Tamping Tobacco in Pipe-Bowls, of which the following is a specification, reference being had to the accompanying drawing, forming part thereof.

Figure 1 is a view in front elevation of a

device for tamping tobacco in pipe bowls. Fig. 2 is a view in side elevation of the device. Fig. 3 is a bottom plan view of the device.

I claim:—

The ornamental design for a device for tamping tobacco in pipe bowls, as shown.

WILFRID LAWSON ROBERTSHAW.
